CLAIM

I claim the ornamental design for a microphone base, as shown and described.

DESCRIPTION

FIG. 1 is a top perspective view showing the top, first side, and front of a microphone base;

FIG. 2 is a front view of the microphone base;

FIG. 3 is a rear view of the microphone base;

FIG. 4 is a first side view of the microphone base;

FIG. 5 is a second side view of the microphone base;

FIG. 6 is top view of the microphone base; and,

FIG. 7 is bottom view of the microphone base.

The broken lines in the drawings are for purposes of illustrating portions of the microphone base that form no part of the claimed design.
